TELEPHONE SYSTEM UTILIZING REGISTER CONTROLLED FINAL SELECTOR SWITCHES

Jacob Kruithof, Ladislas Kozma, and Martinus den Hertog, Antwerp, Belgium, assignors to International Standard Electric Corporation, New York, N. Y., a corporation of Delaware

Application January 16, 1943, Serial No. 472,624
In the Netherlands June 10, 1941.

Section 1, Public Law 690, August 8, 1946
Patent expires June 10, 1961

22 Claims. (Cl. 179—18)

1

The invention relates to new and useful improvements in automatic or semi-automatic telephone systems or similar systems in which final selectors are used.

In the copending applications, Serial No. 472,623, filed January 16, 1943, by Simon, Kruithof, and den Hertog, now Patent No. 2,424,585, dated July 29, 1947 and Serial No. 473,278, filed January 22, 1943, now Patent No. 2,452,578, granted November 2, 1948, by Kruithof, Kozma and den Hertog, inventions are described which are applicable to telephone system and more particularly to group selectors used in such systems.

As is the case with the types of group selectors discussed in the last-mentioned application, various types of final selectors also have characteristic disadvantages which it is the object of the present invention to overcome. The embodiment of the present invention in automatic telephone systems insures the following advantages in the final selectors thereof:

- (a) Simple, one-motion construction;
- (b) Possibility of forming P. B. X groups with a number of outlets larger than the number existing in one group or level of the terminal bank, without introducing any extra complications;
- (c) No marker switch need be provided in association with or individually to each final selector;
- (d) Absence of common control circuits;
- (e) Absence of a marking multiple common to a plurality of final selectors per group, on which only one selection could be made at a time, whereby splitting of this multiple among different final selectors of each group is avoided;
- (f) Absence of artificial load on final selectors when a common control circuit is occupied by one of them;
- (g) Absence of impulsing during any part of the selecting operation, doing away with the customary means for counting impulses at the register controller or at the selector stage;
- (h) High speed operation insured by the kind of signaling system used.

According to the present invention, discriminating signals are employed for setting the final selector on the first terminal of a group or level, or alternatively, on the last terminal preceding such a group or level, whereby the first or last of these terminals is selected under the control of a register controller. This is accomplished by sending signals from the remainder of the terminals, other than the first or last, passed over by the brushes of the final selector which have no effect on the register controller. A sec-

2

ond selection is made to select a predetermined terminal in a group or level, during which all the signals sent from the terminals exercise an influence on the register.

5 The final selector switch may be caused to hunt over a group of lines commonly known as P. B. X group of lines if the first of such a group of lines is found to be busy. Arrangements are disclosed for terminating the P. B. X hunting when the last line of the P. B. X group is reached.

10 Certain lines in a P. B. X group could, according to the present invention, be individually selected without starting the final selector to hunt if the line is busy. This is particularly useful for 15 through-switching at night time, when certain of the P. B. X lines are connected through to particular subscriber stations at the P. B. X and it is not desired to call other stations.

15 The invention will now be described with the aid of the drawings in which one embodiment is diagrammatically shown.

20 Figs. 1 and 2 represent a part of the register controller circuit, which comprises the equipment required to perform the selection in the final selector. Fig. 2 should be placed below Fig. 1.

25 Fig. 3 illustrates the final selector circuit.

Fig. 4 illustrates how one hundred subscribers' line circuits connected to the banks of one group of final selectors are identified or characterized 30 by alternating current sources of different phases and potentials. This drawing shows also the manner in which P. B. X groups of subscriber lines are identified. Fig. 4 is to be placed to the right of Fig. 1.

35 The register circuit is connected over a suitable link and over one or more group selectors having circuits like the final selector of Fig. 3. The operation of the register, as far as the group selectors are concerned, is described in full detail 40 in said application (Kruithof, Kozma, den Hertog, Serial No. 473,278). The following description is therefore limited to the final selector.

45 Fig. 5 is a diagram illustrating the control of tens selection by employing a counting method;

45 Figs. 6 and 7 (to be placed side-by-side) illustrate an alternative P. B. X selecting arrangement; and

50 Fig. 8 illustrates an arrangement for simultaneously controlling the tens and units selections.

I. OPERATION OF THE SYSTEM

The wanted subscriber is indicated to the register by the last two digits of the called number sent by the calling party. These two digits, the

tens and units, are stored on two step-by-step switches SM_T and SM_U, respectively, (Fig. 2).

The drawings do not show how these two digits are received and stored on the two switches, because that is well-known. It is assumed, for the sake of simplicity, that the selection in the final selector starts when both the tens and units digits have been received, although the selecting operation could be started while the tens digit is being sent. As soon as the units digit is received, relay U_{rr} (Fig. 1) is energized, indicating that the selection may start.

The selection in the different group selectors is carried out in successive positions of the step-by-step switch OM as described in the above-mentioned application of Kruithof, Kozma and den Hertog. Fig. 1 shows the positions N, 1 and 2 of OM reserved for such selections. The tens selection will, therefore, start as soon as OM has been advanced to position 3 when the last digits have been received.

(a) TENS SELECTION

Relay Ar (Fig. 3) of the final selector operates as soon as the final selector is seized by a preceding group selector. The operating circuit is described in the last-mentioned application as applied to group selector circuits. Relay Ar locks itself to the "d" brush of the last, e. g. third group selector. The power magnet of the final selector operates in the following circuit: Ground, U_{rr} front, V_{tr} back, (Fig. 2) V_{rr} back, a-wire over all the group selectors, Br back in final, Ar front, magnet P, battery. The brush carriage of the final selector starts to rotate in order to reach the first terminal of that group of subscribers' lines which have the indicated tens digit. These so-called subnormal positions are characterized by the presence of ten different phases of alternating potential having a certain voltage (3 v.) as shown in the following table:

Tens selection

Terminals in final selector arcs	Phase (potential 3 v.)
1	φ ₁
11	φ ₂
21	φ ₃
31	φ ₄
41	φ ₅
51	φ ₆
61	φ ₇
71	φ ₈
81	φ ₉
91	φ ₁₀

The selected one of these alternating current signals is compared with an alternating current signal applied to arc b of SM_T. These two currents are received in the register controller circuit, which has the necessary equipment for comparison. This equipment is shown in Figs. 1 and 2 within the dotted lines and includes transformers, tubes, coils, resistances, and the relay V_{tr}. The operation of this equipment has been described in the above-mentioned applications. The signaling current, to which reference is made in said applications, corresponds here to the alternating current received from the subscribers' line circuits in the final selector, and the reference current is the alternating current connected over brush b of SM_T.

The circuit for the signaling current can be traced as follows: Source of alternating current in the line circuit, brush d of final selector, Br back, Ar front, c-wire, group selectors, V_{hr} back, windings of transformer HC₁, ground. The cir-

cuit of the reference current is as follows: alternating current source, terminal and brush b of SM_T, terminal 3 and brush d of OM, winding of transformer HC₂, ground. The brush d of the final selector wipes over the terminals until the signal receiver detects that the signaling and reference currents are in phase. The tube T₂ becomes then ionized, relay V_{tr} operates and the brush carriage of the final selector stops on the subnormal terminal corresponding to the wanted tens group.

The alternating current sources connected to arc b of SM_T are the same as those connected to the subnormal terminals on the final selector.

15 Relay V_{tr} operates relay Sar in the circuit: Ground, U_{rr} front, V_{tr} front, brush e and terminal 3 of OM, winding of relay Sar, battery.

16 Relay Sar operates relay V_{rr}, whereupon relay Chr releases. Relay Chr is normally kept operated by relay U_{rr} and it connects positive battery of 130 v. to the anode of the cold cathode tube T₂. As soon as relay Chr releases, the tube T₂ extinguishes and relay V_{tr} releases.

17 Relay Sar once operated, locks itself to the interrupter contact of OM, in order to ensure the full operation of the magnet of the step-by-step switch. When the magnet OM opens its back contact and if at that time relay V_{tr} is released, then the relays Sar and V_{rr} also release. The brushes of switch OM make one step and change on arc d the reference current. Relay Chr operates again and the circuit is ready for the units selection.

(b) UNITS SELECTION

18 The subnormal positions of the final selector correspond to the units digit 1. If, therefore, this digit was sent by the subscriber, then the step-by-step switch SM_U will be in position 1 and via brush b of SM_T and brush b of SM_U the reference current characteristic for this subnormal position will be connected. As soon as relay Chr operates, relay V_{tr} prevents the selector switch from leaving the subnormal position occupied and the units selection is thereby terminated.

19 If the units digit is not 1, then the final selector's brush carriage is started again, since relay V_{tr} does not operate. The ten groups of nine terminals, each group lying between two subnormal positions, are multiplied and also connected to the alternating current sources of nine different phases, which have different potentials (2 volts) from those used to characterize the subnormal positions. Complete information concerning these connections is shown in the table below:

Units selection

Terminals in final selector arcs	Phase (potential 2 v.)
2, 12, 22 . . . 92	φ ₂
3, 13, 23 . . . 93	φ ₃
4, 14, 24 . . . 94	φ ₄
5, 15, 25 . . . 95	φ ₅
6, 16, 26 . . . 96	φ ₆
7, 17, 27 . . . 97	φ ₇
8, 18, 28 . . . 98	φ ₈
9, 19, 29 . . . 99	φ ₉
10, 20, 30 . . . 100	φ ₁₀

70 When the final selector encounters the signaling current identical with the reference current, then relay V_{tr} operates and the final selector stops on the circuit of the wanted line.

(c) WANTED LINE IS FREE

71 In this case relay V_{tr} energizes relay V_{hr} via

terminal 4 of the brush *e* of OM. The *c*-wire of the subscriber's line circuit is tested in the following circuit: Ground, *Vhr* front, resistance of 3000 ohms, winding of relay *Pbr*, *b*-wire, group selectors, *Br* back in final selector, *Ar* front, winding I of relay *Br*, brush *c*, winding of relay *Cor* (Fig. 4), battery.

In this circuit only relay *Pbr* operates; the winding of relay *Br*, due to the high resistance of the circuit, does not get sufficient current. Relay *Pbr* energizes relay *Sfr* and this relay connects the low resistance winding relay *Sor* in parallel to relay *Pbr*. Relay *Sor* operates and replaces the function of the contact of relay *Pbr* which, being shunted, releases. The grounding of the terminal, indicated at *F* (Fig. 1) via a front contact of relay *Sfr*, indicates that the subscriber line is free. The control of the four wires *a*, *b*, *c* and *d*, is then taken over by the cord or link circuit, and the register is released in the well-known manner.

Relay *Br* in the final selector operates as soon as relay *Sor* is introduced in shunt to relay *Pbr*. Relay *Br* removes the short circuit from its winding II, and closes a locking circuit to the battery over the 600 ohm resistance. It short circuits its operating winding via a front, which closes later in order to connect through the *c*-wire. The busying ground of the subscriber's line circuit will be provided over a suitable resistance in the cord circuit.

A second winding on relay *Sor* is connected via front contacts of the relays *Sfr* and *Vhr* to the *c*-wire, from which the winding of transformer *HC* has been disconnected. Low resistance ground being now provided on both the *b*- and *c*-wires, relay *Br* in the final selector becomes energized and connects through the wires *b*- and *c*- so as to complete the circuit of relay *Cor*.

(d) SUBSCRIBER BUSY

If the wanted line is busy, then the potential on the *c*-wire is reduced by the busying ground, preventing the relay *Pbr* to operate. The operation of relay *Vhr* is followed by that of relay *Gbr*, which is slow operating in order to cover the operation times of relays *Pbr* and *Sfr* in case the line is free. Relay *Gbr* energizes relay *Pcr* and the latter energizes relay *Sbr* via back of relay *Ps*. The grounding of the terminal *B* (Fig. 1) indicates to the cord circuit or other circuit used in the connection, that the wanted subscriber is busy. The final selector is not connected-through in this case and the cord circuit will release all group and final selectors behind it and will give the busy tone to the calling party.

(e) HUNTING IN P. B. X GROUPS

In P. B. X groups the first and last lines have a resistance *R* connected in parallel to the relay *Cor*.

If the first line of a P. B. X is busy, then relay *Pbr* of the register connected in series with a resistance of 3000 ohms, cannot operate in spite of the reduced resistance of the subscriber's *c*-wire. Relay *Vhr* energizes relay *Gbr* and this closes the circuit for relay *Pcr*. The above-mentioned resistance of 3000 ohms is now short circuited, and relay *Pbr* will operate since the resistance *R* is in parallel to relay *Cor*. The relay *Pbr* does not operate in the above circuit when a single line or an intermediate line of a P. B. X group is contacted by the final selector. P. B. X hunting can, therefore, start only if the first line

of the group is selected. All other lines of the group, except the last, can be called individually.

Relay *Pbr* operates relay *Pgr* in the circuit: ground, *Pbr* front, *Pcr* front, *Pbr* back, winding of relay *Ps*, battery.

Relay *Ps* prepares a locking circuit for itself over relay *Pbr*, and relay *Vrr* is energized in the circuit: ground, relay *Pcr* front, relay *Ps* front, winding of relay *Vrr*, battery.

Relay *Vrr* disconnects relay *Chr*, which releases and extinguishes the tube *T₂*. Relays *Vtr*, *Vhr*, *Gbr*, *Pcr* and *Pbr* release in sequence. The short circuiting ground on relay *Pbr* is removed, so that this relay can now operate in series with relay *Ps*. Relay *Pcr* releases relay *Vrr*, so that relay *Chr* may now again be operated, whereby the receiving circuit is again in testing condition. Relay *Vhr* energizes the magnet of the step-by-step switch *SMu* so that for each test the brushes take one step. By advancing to the next terminal, switch *SMu* changes the reference current to the phase of the next subscriber's line circuit.

As soon as relay *Vrr* releases, the power magnet of the final selector is again energized and the brushes start to rotate again. Due to the correspondence of the phases, the final selector stops on the next terminal and relay *Vtr* starts the same operation as above described. If the second line of the group is free, then relay *Pbr* operates before relay *Gbr* can close its front contact, whereupon relay *Sfr* energizes in the same way as on a single line. If the line is found busy, then relay *Pcr* energizes as soon as relay *Gbr* closes its front contact. Relay *Pcr* energizes relay *Vrr*, the tube *T₂* is extinguished, the brushes of switch *SMu* take one step and the P. B. X hunting continues.

If the last line of the P. B. X is also busy, then relay *Pbr* operates due to the increase of current flowing through its winding as soon as relay *Pcr* operates. Relay *Pfr* operates in the following circuit: Ground, *Pbr* front, *Pcr* front, *Pfr* front, winding of relay *Pfr*, battery.

By grounding terminal *B* relay *Pfr* indicates that the called lines, i. e. all lines of the called P. B. X group are busy.

The brushes of switch *SMu* advance one step for each testing and thus advance the reference current in synchronism with the signaling current. The P. B. X group may contain any number of subscribers' lines. When during the P. B. X hunting the final selector reaches the next subnormal position, the reference current has to be changed in accordance with the signaling current used for the tens selection. This change is effected by relays *Skr* and *Msr*. The former is energized in position 2 of switch *SMu* and remains locked to the interrupter contacts of

both magnets *SMt* and *SMu*. The arrival of *SMu* in its normal position is an indication that the final selector will meet a subnormal position on the next test. Relay *Msr* operates and both magnets *SMt* and *SMu* are energized. When the

terminals on both interrupters are opened, relays *Skr* and *Msr* release and both switches move their brushes one step. The winding of transformer *HC₂* is connected via position 1 of the arc *b* of *SMu* and via arc *b* of *SMt* to the reference current corresponding to the next subnormal position.

II. CIRCUIT VARIATIONS

The above disclosed circuits and operations have been described by way of example only.

This invention is in no way limited to the arrangements described and several alternative methods are possible. By way of example, the following three alternative applications of the principle involved in the new invention will be described:

(a) Alternative method of making tens selection, employing counting principle.

(b) Alternative method of controlling P. B. X hunting.

(c) Alternative method of controlling tens and units selections simultaneously.

(a) COUNTING OPERATION FOR THE TENS SELECTION

The scheme of final selection described in the previous chapter 1 required the use of two series of alternating current sources: one to designate the ten subnormal positions and the other one to designate the terminals between subnormal positions. As was shown, the difference between the two series was in the value of the potential, one having currents of 2 volts and the other currents of 3 volts.

Fig. 5 shows the modifications that must be made in order to perform the final selection with a single series of alternating current sources. Two relays *Ctr* and *Cir* and one step-by-step switch *SM_c* are added to the arrangement shown in the previous figures. The 100 terminals of the final selector have to be connected to the alternating current sources as follows:

Terminals in the final selector	Phase
1, 11, 21 . . . 91	ϕ_1
2, 12, 22 . . . 92	ϕ_2
3, 13, 23 . . . 93	ϕ_3
4, 14, 24 . . . 94	ϕ_4
5, 15, 25 . . . 95	ϕ_5
6, 16, 26 . . . 96	ϕ_6
7, 17, 27 . . . 97	ϕ_7
8, 18, 28 . . . 98	ϕ_8
9, 19, 29 . . . 99	ϕ_9
10, 20, 30 . . . 100	ϕ_{10}

The circuit operation as far as the tens selection is concerned, changes in the following respects:

As above, switch *SM_r* records the tens digit sent by the subscriber. The connection in arc *b* must however be changed as shown in Fig. 5. The brushes of the final selector start to rotate, whereby the power magnet of the selector is operated over the back contacts of relays *Vtr* and *Ctr* in parallel. The primary winding of transformer *HC₂* is during this selection permanently connected to phase *I*.

When the final selector encounters the first terminal *d*, to which the phase *I* is connected, i. e. terminal 1, the receiving equipment responds and relay *Vtr* operates. Relay *Vtr* energizes *Cir* and this in turn operates relay *Vrr*, with the result that the tube *T₂* is extinguished and relay *Vtr* releases, whilst the final selector, driven over the back of relay *Ctr*, continues its rotation.

Relay *Cir* operates magnet *SM_c* and when relay *Cir* releases, the brushes of *SM_c* take one step. The above operation is repeated for each terminal to which the phase *I* is connected (terminals 11, 21 . . .), until relay *Ctr* operates via arc *b* of *SM_c* and arc *b* of *SM_r*. Relay *Ctr* operates after the brushes of *SM_c* have stepped over to the next terminal, thus at a moment when relay *Vtr* has already released.

The final selector continues to rotate until relay *Vtr* operates on the next subnormal terminal, but now the circuit of the power magnet is opened.

Over the front of relay *Vtr* relay *Sar* is energized at present and the tens selection is terminated.

The arcs of terminals *b* of *SM_r* and *SM_c* are interconnected in such a way that relay *Ctr* operates one subnormal position earlier than it otherwise would according to the tens digit, in order to stop the final selector under the control of relay *Vtr* in the usual test circuit.

10 (b) P. B. X GROUP DESIGNATIONS BY ALTERNATING CURRENT

Figs. 6 and 7 show an alternative P. B. X group selection. The designations are derived from thirty different alternating current sources. The first series of ten alternating current sources, which have different phase angles but are of the same frequency *F₁*, are assigned to characterize the individual subscriber's line circuits as shown in connection with Fig. 5. The second series of ten alternating current sources have also ten different phase angles, but another frequency *F₂*. This second series serves to designate the first line of each P. B. X group in such a way that the alternating current source of the first series connected to the *d*-terminal is replaced by that alternating current source of the second series which has the same phase angle. The third series of ten alternating current sources, which have again a different frequency *F₃*, are used to designate the last line of each P. B. X group, in such a way that the alternating current source of the first series connected to the *d*-terminal is replaced by the corresponding alternating current source of the third series.

35 The circuit operation is briefly as follows:

The register controller has three receiving units, I, II and III, instead of one. The transformers *HC₂* are connected over three separate arcs of *SM_u* to the reference current sources of different phases and frequencies. *SM_u* is, as in Fig. 2, the step-by-step switch recording the units digit sent by the calling subscriber.

The circuit of the power magnet of the final selector is controlled over the back contacts of all three *Vtr* relays associated with the three receiving units. The final selector can, therefore, be stopped by any of the three receiving units depending on the frequency of the signaling current connected to the *d*-terminal of the called subscriber. Thus, the receiving unit I responds if the called line is a single line or an intermediate line of a P. B. X group. The unit II energizes on the first line of a P. B. X group and unit III on the last line of a similar group.

In case of a single line relay *Ror₁* is operated. Relay *Tr* is connected to the *c*-wire of the line circuit and, if the wanted line is free, the relays *Tr* and *Dtr* will operate as previously described. The grounding of the terminal-F indicates that the subscriber's line is free. If the line is busy, relay *Tr* fails to operate and therefore relay *Gbr* will be energized. Relay *Gbr* grounds terminal-B via the front contact of relay *Ror₁* and back contact of relay *Psr*, to indicate that the called subscriber is busy.

In case the first line of a P. B. X group is tested, relay *Ror₂* energizes. If the line is free, relays *Tr* and *Dtr* energize, as for single lines. However, if the line is busy, relay *Gbr* operates and relays *Sar* and *Psr* are energized over front contacts of *Ror₂*. Relay *Sar* locks itself to the interrupter contact of *SM_u*, which magnet is energized at the same moment. Furthermore, relay *Sar* operates relay *Vrr* which, in a manner similar to that

shown in Figs. 1 and 2, releases the receiving unit. The release of relay V_{tr} is followed by that of relays R_{0r2} , G_{br} , S_{ar} , V_{rr} , etc. The brushes of switch SM_u take one step in order to change the reference currents of all three frequencies to the next phase. Relay P_{sr} , once operated, locks itself independently of relay R_{0r2} to some ground controlled in the register circuit.

The final selector is now stopped on the second line of the P. B. X group to which the alternating current source of the first frequency F_1 is connected. Relay R_{0r1} operates and if the line is free, the relays Tr and Dtr are energized. If the line is busy, relay G_{br} operates and relay S_{ar} is energized via fronts of relay R_{0r1} and relay B_{sr} . The receiving unit I is released and P. B. X hunting continues until a free line is found.

The receiving unit III responds to the last line of the P. B. X group. Relay R_{0r3} operates and connects relay Tr in the known way to the test wire. If the line is busy, the front of relay G_{br} connects ground to terminal-B via a front of relay R_{0r3} and thus indicates the busy condition.

The advantages of this arrangement are, that no individual P. B. X resistances are required and that, the c-wire of the subscriber line having a constant resistance, regular double test (by relays Tr and Dtr) can be carried out. Furthermore, since different signals are sent for the first and for the last P. B. X line, the last line may be called as an individual line. This is not possible with the arrangement described in chapter I, because the increased c-wire current of the last line would start P. B. X hunting. In the present case, however, the operation of relay R_{0r3} is followed by the regular test, but no P. B. X hunting can start.

The tens selection can be carried out in different ways. The register can, e. g., count the number of subnormal positions over which the brushes of the final selector pass, in the same way as described in chapter II (a). The difference will be that all three receiving units have to be connected and that the phase I will be detected by one of these three units, depending on the subscriber line, i. e. depending on the frequency of the alternating current connected to the d-terminal.

Another method of performing the tens selection is that described in the introduction. This method necessitates thirty more sources of alternating current, which differ from the first thirty only in their potential. Thirty alternating current sources of the frequencies F_1 , F_2 and F_3 of 3 volts potential may, for instance, be used to designate the first position of each group of ten subscribers' lines corresponding to the same tens digit. Depending whether the subscriber's line belonging to this terminal is a single line, or the first or the last line of a P. B. X group, the alternating current sources of frequencies F_1 , F_2 or F_3 will have to be connected. Similarly, the thirty alternating current sources of the frequencies F_1 , F_2 and F_3 of 2 volts potential are used to mark the positions between the subnormal positions (in fact only 3×9 sources are required), and these sources must be connected as required by the subscribers' lines concerned.

The above scheme is given only as an example, and it is evident that the electrical characteristics can be varied in any other convenient way. Another scheme is, for instance, to assign the different potentials P_1 , P_2 , P_3 for indicating single lines, first and last P. B. X lines and to use two different frequencies F_1 and F_2 , one serving for the tens and the other for the units selection.

(C) SIMULTANEOUS CONTROL OF THE TENS AND UNITS SELECTIONS

Fig. 8 shows a circuit arrangement which permits the simultaneous control of the tens and units selections. The receiving equipment is shown split into two parts. One part is the signal discriminating and the other the responding part. The final selector sends over two separate paths, two distinct signaling currents, one representing the tens and the other the units digits of the subscriber's line connected to the terminals engaged by the brushes d and e . The register controller is provided with two signal discriminating units, I connected to the brush d of the final selector, over which the signaling current of the tens is sent, and II connected to brush e of the final selector, over which the signaling current of the units digit is received. This brush e is an additional brush in all final and group selectors and is only required in connection with this scheme.

The reference current of the first discriminating unit is received via arc b of SM_r , which records the tens digit sent by the calling party. The reference current of the second unit is applied over SM_u , which records the units digit.

The outputs of both discriminating units are connected in series. The tube of the responding unit T_2 can only light if in both discriminating units the signaling and reference currents are in phase. The power magnet of the final selector is driven via the back contact of relay V_{tr} , which operates at the moment the brush carriage reaches the terminals of the wanted subscriber.

This arrangement has the advantage that the selection in the final selector can be performed by means of one set of alternating current sources, without counting operation, and that the final selector can be set directly on the wanted terminal without first stopping in a subnormal position. However, an additional conductor is required in the subscriber's line circuit and a fifth brush on all the selector switches.

- What is claimed is:
1. In a telephone exchange system, a plurality of numerically designated lines, switching means including final selectors for connecting a calling with a called line, each of said selectors having sets of bank contacts to which lines are connected, brushes cooperating with said contacts, means for moving said brushes over said contacts in succession, a register controller, an impulse device associated with the calling line for operating said register controller in accordance with the designation of the called line, switches for associating said register controller with a final selector, means directly controlled by the register controller for operating said brushes to select a line in accordance with the tens and units designations thereof, and signals characteristic for the lines sent through the moving brushes of the final selector to the register controller controlling the operation thereof.
  2. The telephone system according to claim 1, characterized in that said final selector includes two relays having contacts controlling all operations thereof.
  3. In a telephone exchange system, a plurality of numerically designated lines, some divided into P. B. X groups, switching means including final selectors for connecting a calling with a called line, each of said selectors having sets of bank contacts to which lines are connected, brushes cooperating with said contacts, means for moving

said brushes over said contacts in succession, a register controller, an impulse device associated with the calling line for operating said register controller in accordance with the designation of the called line, switches for associating said register controller with a final selector, means directly controlled by the register controller for operating said brushes to select a line in accordance with the tens and units designations thereof and to hunt for an idle P. B. X line, and signals characteristic for the lines sent through the moving brushes of the final selector to the register controller controlling the operation thereof.

4. The telephone system according to claim 3, characterized in that said final selector comprises two relays having contacts controlling all operations thereof.

5. In a telephone exchange system, a plurality of numerically designated lines, some divided into P. B. X groups, switching means including final selectors for connecting a calling with a called line, each of said selectors having consecutive sets of bank contacts to which lines are connected, each set including a test contact, brushes cooperating with said contacts, means for moving said brushes over said contacts in succession, a register controller, an impulse device associated with the calling line for operating said register controller in accordance with the designation of the called line, switches for associating said register controller with a final selector, means directly controlled by the register controller for operating said brushes to select a line in accordance with the tens and units designations thereof and to hunt for an idle P. B. X line, a source of electric potentials differing in at least one of their electric properties, means for applying one of said potentials to the test terminals between which a P. B. X group is located, a counting device in the register controller, a signal receiver in the register controller, means for operating the signal receiver in accordance with signaling current having electric properties corresponding to those of the potentials applied to one of said test terminals, means for operating the counting device to count the number of P. B. X line terminals passed over by the brushes of the final selector switch, and means under the joint control of the signal receiver and counting device for controlling the operations of the register controller and the selector.

6. In a telephone exchange system, a plurality of numerically designated lines, switching means including selectors for connecting a calling with a called line, each of said selectors being operable in accordance with two designations of the called line and having sets of bank contacts to which lines are connected, each set including a test contact, the sets of contacts from which one is selected during the selection in accordance with the first designation being located at intervals in the contact bank, and the ones from which one is selected in accordance with the second designation being between contacts selectable in the first selection, brushes cooperating with said sets of contacts, means for moving said brushes over said sets of contacts in succession, a register controller, an impulse device associated with the calling line for operating said register controller in accordance with the designation of the called line, switches for temporarily associating said register controller with a selector, means directly controlled by the register controller for operating said brushes to select a line in accordance with the two designations thereof, a source

of potential, means for applying to the test contacts of the lines from which the first selection is made, potentials of which at least one of the electrical properties is different for each line, means for applying to the intermediate test contacts of the lines, potentials of which at least one of the electric properties is different for the different intermediate lines and of which at least one other electric property is different from that applied to the test contacts of the lines from which the first selection is made, and signals characteristic for said potentials sent through the brushes of the selector to the register controller controlling the operation thereof.

15 7. In a telephone exchange system, a plurality of numerically designated lines, some divided into P. B. X groups, switching means including final selectors for connecting a calling with a called line, each of said selectors having sets of bank contacts to which the called lines are connected, each set including a test contact, brushes cooperating with said sets of contacts, means for moving said brushes over said sets of contacts in succession, a register controller, an impulse device associated with the calling line for operating said register controller in accordance with the designation of the called line, switches for temporarily associating said register controller with a final selector, means directly controlled by the register controller for operating said brushes to select a line in accordance with the tens and units designations thereof and to hunt for an idle P. B. X line, characteristic potentials applied to the test contacts of individual lines and differing in at least one characteristic depending on the busy or idle condition of the line, characteristic potentials applied to the test contacts of P. B. X lines differing in at least two electrical characteristics depending on the busy or idle condition of the P. B. X lines, test means in the controller selectively responsive to said potentials, and signals characteristic for the numerical designations of the lines sent through the moving brushes of the final selector to the register controller controlling the operation thereof.

40 8. In a telephone exchange system, a plurality of numerically designated lines, some divided into P. B. X groups, switching means including final selectors for connecting a calling with a called line, each of said selectors having sets of bank contacts to which the called lines are connected, each set including a test contact, brushes cooperating with said sets of contacts, means for moving said brushes over said sets of contacts in succession, a register controller, an impulse device associated with the calling line for operating said register controller in accordance with the designation of the called line, switches for temporarily associating said register controller with a final selector, means directly controlled by the register controller for operating said brushes to select a line in accordance with the tens and units designations thereof and to hunt for an idle P. B. X line, characteristic potentials applied to the test contacts of individual lines and differing in at least one characteristic depending on the busy or idle condition and the designation of the line, characteristic potentials applied to the test contacts of P. B. X lines differing in at least two electrical characteristics depending on the busy or idle condition of the P. B. X lines, test means in the controller selectively responsive to said test potentials, a discriminator in the controller for controlling the operation of the final selector, means for applying to the discriminator poten-

tials characteristic for the numerical designation of the called line, means for applying to said discriminator the potentials applied to test terminals of the final selector, and means for operating the discriminator when the potentials applied thereto bear a predetermined relationship to one-another.

9. In a telephone exchange system, a plurality of numerically designated lines, switching means including final selectors for connecting a calling with a called line, each of said selectors having sets of bank contacts to which lines are connected, brushes cooperating with said contacts, means for moving said brushes over said contacts in succession, a register controller, an impulse device associated with the calling line for operating said register controller in accordance with the designation of the called line, switches for associating said register controller with a final selector, means directly controlled by the register controller for operating said brushes to select a line in accordance with the tens and units designations thereof, and signals characteristic for the numerical designations of the lines sent through the moving brushes of the final selector to the register controller controlling the operation thereof.

10. In a telephone exchange system, a plurality of numerically designated lines, switching means including final selectors for connecting a calling with a called line, each of said selectors having sets of bank contacts to which lines are connected, each set including two special contacts, brushes cooperating with said contacts, means for moving said brushes over said contacts in succession, a register controller, an impulse device associated with the calling line for operating said register controller in accordance with the designation of the called line, switches for associating said register controller with a final selector, means directly controlled by the register controller for operating said brushes to select a line in accordance with the tens and units designations thereof, potentials characteristic for the tens digit of the lines applied to one special contact thereof, potentials characteristic for the units digit applied to the other special contact thereof, and circuits for controlling the register controller including said special contacts.

11. In a telephone exchange system, a plurality of numerically designated lines, some divided into P. B. X groups, switching means including final selectors for connecting a calling with a called line, each of said selectors having sets of bank contacts to which lines are connected, brushes cooperating with said contacts, a magnet for moving said brushes over said contacts in succession, a register controller, an impulse device associated with the calling line for operating said register controller in accordance with the designation of the called line, switches for associating said register controller with a final selector, a circuit for said magnet, a relay in the register controller for closing said circuit to move said brushes to select a line in accordance with the tens and units designations thereof and to hunt for an idle P. B. X line, a source of potential, means in said register controller for applying potentials of certain characteristic to said relay depending on the setting of said controller by the impulse device, means in said selector for applying potentials of certain characteristic to said relay depending on the setting of the brushes on certain contacts, and means for operating said relay only if the two potentials applied thereto bear a predetermined relationship to one-another.

12. In a telephone exchange system, a plurality of numerically designated lines, some divided into P. B. X groups, switching means including final selectors for connecting a calling with a called line, each of said selectors having sets of bank contacts to which lines are connected, brushes cooperating with said contacts, a magnet for moving said brushes over said contacts to select a line in accordance with the tens and units designations thereof and to hunt for an idle P. B. X line, a register controller, an impulse device associated with the calling line for operating said register controller in accordance with the designation of the called line, switches for temporarily associating said register controller with a final selector, a source of potentials, means for applying to contacts of a line various classes of characteristic potentials identifying the line, a plurality of means in said register controller, each responsive to a different class of characteristic potentials, a switch in said register controller and controlled by the impulse device for selecting a particular characteristic potential, and a circuit for said magnet jointly controlled by the last-mentioned switch and said plurality of means.

13. In a telephone exchange system, a plurality of numerically designated lines, switching means including final selectors for connecting a calling with a called line, each of said selectors having sets of bank contacts to which individual lines and a group of P. B. X lines are connected, brushes cooperating with said contacts, a magnet for moving said brushes over said contacts in succession, means for making busy lines with whose contacts the brushes of a selector are connected, and for preventing the selection of a busy line by a selector, a register controller, an impulse device associated with the calling line for operating said register controller in accordance with the designation of the called line, switches for associating said register controller with a selector, two relays associated with each selector, circuits controlled by the register controller for operating said relays to control all operations of said selector, to select a line in accordance with the tens and units designations thereof, and to select an idle P. B. X line.

14. The telephone system according to claim 13, characterized in that talking conductors terminate in two brushes, and in contacts of one of said relays, and a circuit for said one of said relays closed by said register controller upon the selection of a free line to switch through said talking conductors.

15. The telephone system according to claim 13, characterized in that a source of direct current potential is provided at the called line to prevent simultaneous selection of the line by more than one selector, and that one of said relays has a winding connected in series with said source of potential, and a test relay at the register controller in said circuit.

16. The telephone system according to claim 13, characterized in that a source of D. C. potential is provided at the called line to prevent simultaneous selection of the line by more than one selector, and that one of said relays has two windings, a circuit for one of said windings extending from said source to said register controller, and a circuit for the other winding independent of the register controller and the direct current potential at the engaged line, providing a metallic connection to a brush of the final selector.

17. In a telephone exchange system, a plurality of numerically designated individual lines and a

group of P. B. X lines, switching means including final selectors for connecting a calling with a called line, each of said selectors having sets of bank contacts to which lines are connected, each set including a test contact, brushes cooperating with said contacts, means for moving said brushes over said contacts in succession, a register controller, an impulse device associated with the calling line for operating said register controller in accordance with the designation of the called line, switches for associating said register controller with a final selector, means directly controlled by the register controller for operating said brushes to select a line in accordance with the tens and units designations thereof and to hunt for an idle P. B. X line, a source of direct current potential, means for applying busy potentials to the test contacts of busy first and last P. B. X lines and different busy potentials to the test contacts of other P. B. X lines, a second source of potential, means for applying from said second source a characteristic potential to certain contacts in said bank characteristic for the numerical designation of the line connected therewith, and means in the register controller responsive to both potentials applied to the bank contacts of the selector for controlling the operation of the latter.

18. The telephone system according to claim 17, characterized in that the register controller comprises a marginal relay, means controlled by the marginal relay to initiate the hunting action of the final selector from a selected busy first line of a P. B. X group, a circuit for said marginal relay including said source of direct current potential, said marginal relay being adjusted to operate only when the brushes engage contacts of idle lines, but to operate when the brushes engage contacts of busy first or last lines of a P. B. X group, and means for operating said brushes to select any of the other contacts in accordance with the numerical designation thereof without initiating the hunting action if the selected line is found busy.

19. The telephone system according to claim 17, characterized in that the register controller

comprises a marginal relay, means controlled by the marginal relay to initiate the hunting action of the final selector from a busy first line of a P. B. X group, and a circuit for said marginal relay including said source of direct current potential to operate only when the brushes engage the contacts of a busy first line of a P. B. X group.

20. The telephone system according to claim 1, characterized in that the register controller starts the selecting operation of the selector while impulses representing said selecting operation are received by the register controller.

21. The telephone system according to claim 1, and in which the register controller controls the operation of said selector in accordance with two digits of the called number, characterized in that said register controls the operation of the selector in accordance with one digit while impulses representing said digit are being received by the controller.

22. The telephone system according to claim 1, an electrical discharge device in the register, sources of different electrical potentials, means for applying a potential to the discharge device responsive to the operation of the register controller under the control of the impulse device, means for applying a second potential to the discharge device over a bank contact and a brush of the operated final selector and said switches, and means operated by the discharge device when the two potentials applied thereto bear a predetermined relationship to one-another for stopping the movement of the final selector brushes.
